CLAIM

The ornamental design for post protector, as shown and described.

DESCRIPTION

FIG. 1 is an upper front left perspective view of the novel assembled post protector.

FIG. 2 is an upper front perspective view of the assembled post protector of FIG. 1.

FIG. 3 is a lower front left perspective view of the assembled post protector of FIG. 1.

FIG. 4 is a lower front perspective view of the assembled post protector of FIG. 1.

FIG. 5 is a front view of the assembled post protector of FIG. 1.

FIG. 6 is a rear view of the assembled post protector of FIG. 1.

FIG. 7 is a left side view of the assembled post protector of FIG. 1.

FIG. 8 is a right side view of the assembled post protector of FIG. 1.

FIG. 9 is a top view of the assembled post protector of FIG. 1.

FIG. 10 is a bottom view of the assembled post protector of FIG. 1.

FIG. 11 is an upper front left perspective view of a single panel of the assembled post protector of FIG. 1.

FIG. 12 is a front perspective view of the single panel of FIG. 11.

FIG. 13 is a lower front right perspective view of the single panel of FIG. 11.

FIG. 14 is a rear perspective view of the single panel of FIG. 11.

FIG. 15 is a front view of the single panel of FIG. 11.

FIG. 16 is a rear view of the single panel of FIG. 11.

FIG. 17 is a left side view of the single panel of FIG. 11.

FIG. 18 is a right side view of the single panel of FIG. 11.

FIG. 19 is a top view of the single panel of FIG. 11; and,

FIG. 20 is a bottom view of the single panel of FIG. 11.
